SNUBBED SPRING GROUP

Lawrence F. Ramos and Otto W. Neumann, Chicago, Ill., assignors to American Steel Foundries, Chicago, Ill., a corporation of New Jersey

Application February 7, 1951, Serial No. 209,809

12 Claims. (Cl. 267—9)

This invention relates to friction snubbing devices and more particularly to a novel package spring group incorporating such a device and adapted for suspension of a freight car truck bolster.

A primary object of the invention is to devise a friction device such as above described which is adapted to accommodate relative rocking movement between the bolster and its supporting frame which carries the friction device and spring group.

A further object of the invention is to accommodate automatic adjustment of the friction shoes to compensate for wear which normally takes place between the shoes and friction surfaces of such devices.

A further object of the invention is to devise a novel package spring group wherein relative rocking movements of the bolster and frame are resiliently resisted without substantial development of friction, and vertical movements of the bolster are resiliently and frictionally resisted.

The foregoing and other objects and advantages of the invention will become apparent from a consideration of the following specification and the accompanying drawings, wherein:

Figure 1 is a transverse vertical sectional view of a package spring group embodying the invention, the section being taken in a vertical plane approximately bisecting the group on its transverse axis about which the group is symmetrical;

Figure 2 is a fragmentary end view of the group shown in Figure 1, partly in section along the plane indicated by the line 2—2 thereof;

Figure 3 is a sectional view on line 3—3 of Figure 2.

Describing the invention in detail, the novel package spring group comprises a top plate or follower generally designated 2 and having a depending flange 4 about its perimeter to confine the upper ends of a plurality of conventional truck springs 6, adapted to support the load of an associated truck bolster (not shown) which normally seats on the top plate or follower 2 and is positioned by lugs or bosses 8 thereof.

The lower ends of the springs 6 are supported by a bottom plate or follower 10 adapted to seat on the frame (not shown) of a freight car truck and to be positioned relative thereto by depending lugs or bosses 12. The plate or bottom follower 10 is preferably in the form of a casting having lateral flanges 14 at the sides thereof adapted to confine the lower ends of the springs 6 and integrally formed with upstanding panels or walls 16 to which wear plates 18 are preferably secured in any convenient manner, as for example, by welding at 20.

The bottom follower 10 also comprises side walls 19 having slots or recesses 21 in their upper edges, for a purpose hereinafter described. As best seen in Figure 2, the bottom plate or follower 10 is also provided with end flanges 22 confining the springs 6 and each being re-flanged as at 24 to define a substantially horizontal projection or lug with an opening 26 receiving a bolt and nut assembly 28 which projects through a similar opening 30 in a lug or projection 32 formed as a re-flanged portion of the top follower flange 4. The upper end of the bolt and nut assembly 28 is preferably secured as by welding at 34 to the lug 32 and is reciprocal within the opening 26, as the novel package group is alternately compressed and released under operating conditions. As shown at the left of Figure 2, a removable plate or bar 36 bears against the underside of the lug 24 and against

2

an annular stop plate or washer 38, secured as by welding at 40 to the bolt and nut assembly 28. Thus the plate 36 and the corresponding plate at the opposite end (not shown) of the novel spring group function to maintain it under pre-compression during assembly of the device in an associated freight car truck. Upon removal of the plate 36, the springs 6 urge the stop washer 38 against the underside of the lug or web 24 to limit expansion of the package group.

10 The novel friction device of the package group comprises a pair of friction shoes 42, generally triangular in shape, as seen in the sectional view of Figure 1, and each having a pair of arms or lugs 44 formed with hubs 46 rockably engageable as at 48 with the top plate or follower 2, upon compression of the spring group. The hubs 46 are received within a slot 50 defined by a depending U-shaped bar or web 52 formed on the underside of a top plate 2. The bar 52 is provided with an arcuately upwardly facing surface 54 engageable with complementary surfaces of the hubs 46 upon expansion of the spring group. Thus an articulated or jointed connection is provided between the friction shoes 42 and the top follower 2. The bar 52 is adapted for reception within the slots 21 of the walls 19 upon compression of the group. Thus, as will be readily seen in Figure 1, transverse rocking of the upper follower 2 relative to the lower follower 10 is accommodated at all times.

15 The friction shoes 42 are provided, respectively, with wedge faces 55 converging upwardly, as seen in Figure 1, 20 toward the bar 52 and engageable with complementary surfaces of a hollow wedge 56 containing the upper end 25 of a compression coil spring diagrammatically indicated at 58.

20 The lower end of the spring 58 is seated against the bottom follower 10, and the upper end of the spring 58 is seated as at 60 against a spring seat of the wedge lying in a substantially horizontal plane intersecting the shoe surfaces 55, as well as the surfaces of the wear plates 18 against which the shoes 42 are urged by the wedge 56 under the action of its spring 58.

25 As best seen in Figure 3, the arms 44 of each shoe are alternately arranged or interlaced with the arms 44 of the other shoe to position the shoes against relative displacement longitudinally of the spring group and to afford a compact arrangement wherein maximum bearing areas are afforded at 48 and 55 for the hubs 46 of the shoes upon compression and release, respectively, of the novel package group.

30 Referring to Figure 1, it will be seen that the top plate or follower 2 may rock at any given time during compression and release of the spring group on an axis approximately parallel to the friction faces of the wear plates 18 against which the shoes 42 are engaged. Thus assuming that the package group is in normal expanded position, this rocking action may take place without urging the shoes 42 upwardly or downwardly against the plates 18 so that the rocking action is yieldingly resisted, by springs 6, without substantial development of friction. This arrangement affords a soft cushioning resistance to such rocking movements when the package group is in normal released position. However, it will also be seen in Figure 1, that such rocking movements of the top follower 2, accompanied by vertical movements thereof, is effective to develop friction between the shoes 42 and the wear plates 18, and extreme rocking movements of the top follower 2 may cause engagement thereof with the upwardly facing surfaces of the arms 44 of one shoe, thereby urging it downwardly relative to the other shoe to increase frictional resistance to such excessive rocking action.

35 It may be noted that the preferred embodiment illustrated shows only one pair of shoes 42 and one shoe actuating spring 58, however, it will be understood that, if desired, these parts may be multiplied.

36 We claim:

41 1. In a friction device of the class described, a pair of followers, one of said followers having spaced friction surfaces, friction shoes having articulated connections to the other follower on a common axis approximately 46 parallel to said surfaces and extending horizontally intermediate said surfaces, wedge means engageable with

and interposed between said shoes for urging them against respective surfaces, and spring means compressed between the wedge means and said one follower for actuating said wedge means.

2. In a friction device of the class described, a follower having spaced friction surfaces, friction shoes engageable with respective surfaces, another follower hinged to said shoes, a resilient unit carried by one follower and operatively engaged with the shoes for urging them against said surfaces, and converging abutments on each shoe and said other follower engageable during extreme rocking movement of the latter to urge said shoe along the related surface.

3. In a friction device of the class described, a follower having spaced opposed friction surfaces, friction shoes engageable therewith, and means for resiliently urging said shoes against said surfaces, and another follower rockably seated against upwardly facing converging surfaces on said shoes, said other follower having means underlying said upwardly facing surfaces and rockably engageable with downwardly facing surfaces of said shoes upon expansion of the device, said means accommodating pivotal movement of the shoes relative to the other follower on an axis extending parallel to said friction surfaces.

4. In a friction device of the class described, a follower having spaced friction surfaces, friction shoes engageable with said surfaces and having interlaced arms formed at their extremities with hubs, another follower having a slot receiving said hubs and snugly confining the same to rockably interlock the other follower with said hubs, and means carried by the first-mentioned follower for yieldingly engaging the shoes with said surfaces.

5. In a friction device of the class described, a follower having spaced friction surfaces, friction shoes engageable with respective surfaces, another follower having opposed facing abutment surfaces, said shoes having arcuate hubs extending between the last-mentioned surfaces and engageable therewith along a single plane extending between the friction surfaces and approximately parallel thereto, and means for urging the shoes against the friction surfaces.

6. In a package spring group, spaced spring plates, a plurality of springs compressed therebetween, members on one of said plates carrying opposed friction surfaces, friction shoes engageable with respective surfaces, a bar carried by the other plate on the inner side thereof and defining a slot therewith, curved hubs on said shoes projecting into said slot for rockable engagement with said bar and other plate on the expansion and compression strokes, respectively, of the group, a wedge engaged with said shoes along surfaces converging toward the bar, and spring means compressed between said wedge and said one plate for urging the wedge into engagement with the shoes and thereby urging the shoes against the related friction surfaces.

7. In a package spring group, spaced spring plates, a plurality of compression springs interposed therebetween, members having spaced friction surfaces on one of the plates, spaced friction shoes hinged to the other plate, wedge means between said shoes in wedge engagement therewith, and a compression spring between said wedge means and said other plate.

8. In a package spring group, spaced spring plates, a plurality of compression springs interposed therebetween, and a friction device in parallel with said springs, said device comprising members having friction surfaces on one of the plates, friction shoes engageable with said surfaces, wedge means for urging the shoes into engagement with said surfaces, a compression spring between said wedge means and said plate, and means hinging the shoes to the other plate for rocking movement relative thereto on an axis defined by a plane bisecting the last-mentioned spring and passing between said surfaces without intersecting them.

9. In a friction device of the class described, a pair of followers, friction shoes in frictional engagement with one of the followers, a compression spring carried by said follower, wedge means operatively connected to the spring and engaged with the shoes for actuation thereof, and interlaced arms on said shoes hinged to the other follower.

10. A friction device of the class described, comprising spaced followers, friction shoes having interlaced arms rockably hinged to one of the followers, and a resilient unit in pressured engagement with the shoes and the other follower for urging the shoes into frictional engagement with said other follower.

11. A friction device of the class described comprising a pair of followers, friction shoes hinged on a fixed axis to one of the followers, and means carried by the other follower for urging the shoes into frictional engagement therewith, said means comprising a compression spring having a compressional axis passing through the hinge axis of the shoes.

12. In a friction device of the class described, spaced parallel resiliently interconnected followers, at least one friction surface on one of said followers, at least one friction shoe cooperating with said surface and having an articulated connection to the other of said followers, said connection accommodating pivotal movement of said shoe on an axis parallel to the followers and the surfaces, resilient means engaging said one follower and urging said shoe into pressured contact with said surface, said resilient means comprising a wedge, and means to guide the wedge into engagement with said shoe.
